US0D1049815S

(12) **United States Design Patent** (10) **Patent No.:** **US D1,049,815 S**
(45) **Date of Patent:** **** Nov. 5, 2024**

(54) **PIPELINE ANGLE HOLDER**

(71) Applicant: **Beijing Roborock Technology Co., Ltd.**, Beijing (CN)
(72) Inventors: **Zhibin Zhang**, Beijing (CN); **Hongjian Gong**, Beijing (CN); **Xiaoming Liu**, Beijing (CN)
(73) Assignee: **Beijing Roborock Technology Co., Ltd.**, Beijing (CN)

(**) Term: **15 Years**

(21) Appl. No.: **35/518,340**

(22) Filed: **Jun. 28, 2023**

(80) **Hague Agreement Data**

Int. Filing Date: **Jun. 28, 2023**
Int. Reg. No.: **DM/231228**
Int. Reg. Date: **Jun. 28, 2023**
Int. Reg. Pub. Date: **Sep. 15, 2023**

(30) **Foreign Application Priority Data**

Jan. 4, 2023 (CN) 202330002022.1
Jan. 4, 2023 (CN) 202330002027.4
Jan. 4, 2023 (CN) 202330002031.0

(51) **LOC (14) Cl.** **09-06**

(52) **U.S. Cl.** **USPC** **D8/356; D13/155**

(58) **Field of Classification Search**
USPC D8/373, 356, 357, 377, 384; 13/155

(57) **CLAIM**

The ornamental design for a pipeline angle holder as shown and described.

DESCRIPTION

1.1 is a front view of a first embodiment of pipeline angle holder, showing the new design;

1.2 is a back view thereof;

1.3 is a left view thereof;

1.4 is a right view thereof;

1.5 is a top view thereof;

1.6 is a bottom view thereof;

1.7 is a front, top perspective view thereof;

1.8 is a left, top perspective view thereof;

1.9 is a bottom perspective view thereof;

1.10 is another bottom perspective view thereof;

1.11 is a left bottom perspective view thereof;

2.1 is a front view of a second embodiment of pipeline angle holder, showing the new design;

2.2 is a back view thereof;

2.3 is a left view thereof;

2.4 is a right view thereof;

2.5 is a top view thereof;

2.6 is a bottom view thereof;

2.7 is a front, top perspective view thereof;

(Continued)

2.8 is a left, top perspective view thereof;
 2.9 is a bottom perspective view thereof;
 2.10 is another bottom perspective view thereof; and
 2.11 is a left bottom perspective view thereof.

1 Claim, 12 Drawing Sheets

(58) Field of Classification Search

CPC H02G 3/06; H02G 3/0418; H02G 3/0437;
 G02B 6/4459
